UNITED STATES PATENT OFFICE.

SAMUEL M. KINTNER, OF PITTSBURGH, PENNSYLVANIA, ASSIGNOR TO WESTINGHOUSE ELECTRIC & MANUFACTURING COMPANY, A CORPORATION OF PENNSYLVANIA.

POLYPHASE PLATE-CIRCUIT-EXCITATION SYSTEM.

Application filed October 25, 1921. Serial No. 510,383.

To all whom it may concern:

Be it known that I, SAMUEL M. KINTNER, a citizen of the United States, and a resident of Pittsburgh, in the county of Allegheny and State of Pennsylvania, have invented a new and useful Improvement in Polyphase Plate-Circuit-Excitation Systems, of which the following is a specification.

10 My invention relates to oscillation-generator systems and particularly to such systems as are adapted to be energized by polyphase currents.

One object of my invention is to provide 15 an oscillation-generator system which may be energized by three-phase alternating currents of commercial frequency.

Another object of my invention is to provide 20 a polyphase plate-circuit-excitation system wherein the modulating effect of the impressed alternating electromotive force upon the oscillatory currents may be so nullified as to admit of the radiation of energy that shall be constant in amplitude and in 25 frequency.

These and other objects and applications 30 of my invention, whereby the same may be practiced, will be apparent from the following description, when taken in connection with the accompanying drawing and claims.

Heretofore, in signaling systems employing vacuum tubes as oscillation generators, it has been customary to energize the plate-filament circuits of the tubes from direct-current sources of energy, such, for example, as direct-current generators. As the size 35 of the vacuum-tube oscillators is increased, however, considerable difficulty is experienced in obtaining the higher plate voltages required, thereby necessitating, in many cases, dynamos of special construction.

Such difficulties, on the other hand, are not present in alternating-current systems, as any voltage may easily be obtained by 45 employing transformers having the proper ratio. A disadvantage, however, of the single-phase alternating-current systems, heretofore proposed, resides in the fact that the oscillating currents generated by the 50 tubes are modulated at frequencies corresponding to those of the impressed supply currents, thereby resulting in the radiation of modulated energy.

In my invention, such difficulties, as those 55 just mentioned, have been overcome by em-

ploying a three-phase supply system with a pair of oscillation generators for each phase. The modulated oscillatory currents generated by each pair of oscillation generators may be combined in a single radiating system to result in the passage of currents therein which are substantially constant in amplitude and in frequency, all as will be hereinafter more fully described.

My invention may best be understood by 60 reference to the accompanying drawing, in which the single figure is a diagrammatic view of circuits and apparatus embodying my invention.

In the drawing, is shown a plurality of 65 oscillation-generator systems 1, 2 and 3 energized by phases 4, 5 and 6 of a polyphase source of energy of, preferably, true sine-wave form and operatively coupled to an antenna system 7 by means of coupling 70 transformers 8, 9 and 11, respectively.

The antenna system 7 comprises an antenna 12, a tuning coil 13, secondary windings 14, 15 and 16 of the transformers 8, 9 and 11, respectively, and a ground conductor 75 17.

Each oscillation-generator system comprises a pair of vacuum-tube oscillation generators 18 and 19, the output or plate-filament circuits of each being oppositely associated with respect to a common portion 80 21. The portion of the output circuits common to each pair of oscillation generators may include a condenser 22, around which one phase of the polyphase source of energy is connected, and a primary winding 90 23 of the coupling transformers.

The vacuum-tube oscillation generators, in each system, for convenience of illustration, are shown as three-electrode tubes of a type 95 well known in the art and comprise a filament 21', a grid 22' and an anode 23'. The filament 21' may be energized by means of a source of energy 24 through a resistor 25. A plate-filament circuit comprises the condenser 22, the primary winding 23 of one of the coupling transformers and a coil 26 of a feed-back transformer 27. The coil 26 may be shunted by means of a variable condenser 28.

Energy may be supplied to the grid-filament circuit necessary to sustain the oscillations in the plate-filament circuit through the feed-back transformer 27, the remaining coil 29 of which is included in the grid- 100 105 110

filament circuit. As shown in the drawing, the grid-filament circuit is also electrically connected to the plate-filament circuit by means of a conductor 31 which connects corresponding terminals of the coils 26 and 29. The high-frequency oscillations in the plate-filament circuit are prevented from traversing the supply circuit by means of reactors 32 which are included in the supply conductors of each phase.

In operation, when power is supplied to the oscillation-generator systems 1, 2 and 3, sustained oscillatory currents are caused to traverse the plate-filament circuits of each oscillator tube during those portions of the cycle when the impressed electromotive force in the plate circuit is positive in value. Thus, the primary winding 23 of each of the transformers 8, 9 and 11 is traversed by currents generated by one tube during one half-wave of the impressed electromotive force and by currents generated by the remaining tube during the other half-wave of the impressed electromotive force.

While the resultant oscillatory currents traversing each of the primary windings 23 of the coupling transformers 8, 9 and 11 are thus modulated at a frequency corresponding to the supply current, the combined effect of all of the oscillatory currents in the antenna circuit 7 is to produce an oscillating current of substantially constant amplitude and frequency.

The radiation of the energy in the antenna circuit may be modulated by any means well known to the art and, as the modulation means forms no part of my invention, it has been omitted.

It will be noted that, while I have shown oscillation-generator systems of a particular type, my invention is not limited thereto. I desire, therefore, that only such limitations shall be imposed upon my invention as are indicated in the appended claims.

I claim as my invention:

1. In a wireless transmission system, the combination with a polyphase power source, of a plurality of oscillation-generator systems, said systems being oppositely connected in pairs to the respective phases of said polyphase source, and a circuit associated with all of said pairs of oscillation-generator systems and adapted to be energized thereby.

2. In a wireless transmission system, a polyphase power source, a plurality of pairs of oscillation-generator systems, said systems being oppositely connected in pairs to the respective phases of said polyphase source, a common element for each of said pairs of oppositely connected systems and a circuit including means associated with said common elements, whereby said circuit may be energized by said oscillation-generator systems.

3. In a wireless transmission system, a plurality of pairs of oscillation-generator systems, each pair of oscillation generators being oppositely associated with respect to a common element, a polyphase power source to provide one phase for each pair of oscillation generators, said phases being oppositely associated with the oscillation generator in each pair, and a circuit operatively associated with said elements, whereby said circuit may be energized by said oscillation-generator systems.

4. In a wireless transmission system, a plurality of pairs of oscillation generators, each pair of oscillation generators having output circuits, an element common to said output circuits and oppositely associated therewith, a polyphase power source to provide one phase for each pair of oscillation generators, each phase being oppositely associated with the oscillation generators in each pair, and a circuit including means associated with said elements, whereby said circuit may be energized by said oscillation-generator systems.

5. In a wireless transmission system, a plurality of pairs of oscillation generators, each pair of oscillation generators having output circuits, an element common to said output circuits and oppositely associated therewith, a polyphase source of electromotive force to provide one phase for each pair of oscillation generators, each phase being oppositely associated with the oscillation generators in each pair, and a radiating circuit operatively connected to said elements, whereby said radiating circuit may be energized by said oscillation generators.

6. In a wireless transmission system, a plurality of pairs of oscillation generators, each pair of oscillation generators having output circuits, said output circuits in each pair having a common conductor and being oppositely associated therewith, a polyphase source of energy to provide one phase for each pair of oscillation generators, said phases being operatively connected to said common conductor, and a radiating circuit operatively associated to said oscillation generator systems and adapted to be energized thereby.

7. In a wireless transmission system, a plurality of pairs of vacuum-tube oscillation generators, each pair of vacuum tubes having output circuits, said output circuits having a common conductor and being oppositely associated therewith, a polyphase source of energy to provide one phase for each pair of oscillation generators, each phase being connected to said common conductor, and a radiating circuit operatively associated with said oscillation-generator systems and adapted to be energized thereby.

8. In a wireless transmission system, a polyphase source of energy, a plurality of

- pairs of vacuum-tube oscillation generators, one for each phase, each pair of oscillation generators being so connected as to utilize both half waves of the impressed electromotive force, and a radiating system operatively associated with said pairs of vacuum-tube oscillation generators and adapted to be energized thereby.
9. In a wireless transmission system, a polyphase source of energy, a plurality of pairs of oscillation generators, one for each phase, one oscillation generator in each pair being adapted to generate oscillatory currents during one half wave and the remaining oscillation generator being adapted to generate oscillatory currents during the remaining half wave of each cycle of the impressed electromotive force, each of said pairs of oscillation generators including a common coil, and a radiating system including means operatively associated with said common coils, whereby said radiating system may be energized.
10. In a wireless transmission system, the combination with a symmetrical polyphase power source, of a plurality of pairs of oscillation generators, one pair for each phase, the oscillation generators of each pair being oppositely connected to the respective phases, and a common circuit energized by all said oscillation-generators, whereby a uniform sustained oscillating current is produced in said common circuit.

In testimony whereof, I have hereunto subscribed my name this 18th day of October, 1921.

SAMUEL M. KINTNER.
